[57] CLAIM

The ornamental design for a measuring-dispensing spoon or the like, substantially as shown and described.

DESCRIPTION

FIG. 1 is a side elevational view of a measuring-dispensing spoon or the like showing my new design, the side opposite being a mirror image thereof;
FIG. 2 is a top plan view thereof; and
FIG. 3 is a cross-sectional view thereof taken on line 3—3 of FIG. 2.
